WITNESS:

UNITED STATES PATENT OFFICE.

LUDWIG D. LUTTNER, OF WYLIE, MINNESOTA.

TOOL-HOLDER.

1,384,669.

Specification of Letters Patent. Patented July 12, 1921.

Application filed May 24, 1920. Serial No. 383,860.

To all whom it may concern:

Be it known that I, LUDWIG D. LUTTNER, a citizen of the United States, residing at Wylie, in the county of Red Lake and State 5 of Minnesota, have invented new and useful Improvements in Tool-Holders, of which the following is a specification.

This invention relates to tool holders and has for its object the provision of a device 10 adapted to be secured within the pocket of the wearer, as for instance in an overalls pocket, and so constructed as to hold a pair of pliers in position so that they cannot be lost and yet so that they can be conveniently 15 grasped when their use is needed.

An important object is the provision of a device of this character which will be extremely simple and inexpensive in manufacture, highly efficient in use, durable in 20 service, and a general improvement in the art.

With the above and other objects and advantages in view, the invention consists in the details of construction to be hereinafter 25 more fully described and claimed, and illustrated in the accompanying drawings in which—

Figure 1 is an elevation of my device showing a pair of pliers therein, and

Fig. 2 is a side elevation thereof.

Referring more particularly to the drawings, the numeral 10 designates a plate of sheet metal of elongated rectangular form which is bent intermediate its ends, as shown 35 at 11 to provide a bottom portion and which is rebent upon itself to provide a portion 12 extending in spaced parallel relation to the body 10. The corners of this portion 12 are preferably diagonally cut away, as shown 40 at 13, though this is not essential.

Secured upon the extremity of the portion 12, as by a rivet 14, is a spring 15 which is bent intermediate its ends, as shown at 16, so as to be disposed close to the body portion 45 10 and the extremity 17 of the spring extends an appreciable distance away from the plate body 10.

In order that the device may be held securely within the pocket of overalls or other 50 garment, I provide the plate with a plurality of holes 18 through which may be passed cords or the like securing the device within the pocket.

The device is intended particularly for

use in holding pliers designated by the letter 55 A, and the pliers are engaged within the device by inserting them between the portion 16 of the spring and the plate 10 and forcing them downwardly into the space between the plate body 10 and the portion 12 thereof. 60 As the pliers are thus forced downwardly, the portion 16 of the spring will snap past the head of the pliers and redispone itself adjacent the plate portion 10 so as to form a stop which will prevent the pliers from being 65 jostled out of the device. When the operator has need of the device it is merely necessary that he grasp the handles of the pliers and pull them out of the device in a very obvious manner.

From the foregoing description and a study of the drawings it will be apparent that I have thus provided a very simply constructed and consequently very inexpensive device which may be secured within a garment pocket and which is particularly adapted for holding a pair of pliers in convenient position so that they may be readily used but which will positively prevent loss of the pliers.

While I have shown and described the preferred embodiment of my invention, it is of course to be understood that I reserve the right to make such changes in the form, construction, and arrangement of parts as 85 will not depart from the spirit of the invention or the scope of the subjoined claim.

Having thus described my invention, I claim:

A tool holder comprising an elongated 90 rectangular metallic plate formed at one end with an upwardly extending retaining portion disposed in spaced parallel relation to the plate, said plate being adapted for disposition within the user's pocket and being 95 provided with holes for the passage of securing means, and an upwardly extending leaf spring disposed longitudinally of the plate and having its lower end secured to the upper end of said retaining portion and 100 being bent intermediate its ends whereby to engage against the plate with its upper extremity bent away from the plate to define a flaring entrance opening between the plate and the spring.

In testimony whereof I affix my signature.

LUDWIG D. LUTTNER.
